(57) **CLAIM**

The ornamental design for an electrical device, as shown and
described.

DESCRIPTION

FIG. 1 is a front perspective view of a first embodiment of
an electrical device illustrating my new design;

FIG. 2 is a front view of the first embodiment of FIG. 1;
FIG. 3 is a rear view of the first embodiment of FIG. 1;
FIG. 4 is a right side view of the first embodiment of FIG.
1;

FIG. 5 is a left side view of the first embodiment of FIG. 1;
FIG. 6 is a top view of the first embodiment of FIG. 1;
FIG. 7 is a bottom view of the first embodiment of FIG. 1;
FIG. 8 is a front perspective view of a second embodiment
of an electrical device illustrating my new design;

FIG. 9 is a front view of the second embodiment of FIG. 8;
FIG. 10 is a rear view of the second embodiment of FIG. 8;
FIG. 11 is a right side view of the second embodiment of
FIG. 8;

FIG. 12 is a left side view of the second embodiment of FIG.
8;
FIG. 13 is a top view of the second embodiment of FIG. 8;
and,
FIG. 14 is a bottom view of the second embodiment of FIG.
8.

In the drawings, the dot-dash broken lines represent a
boundary to the claimed design. The remaining dash-dash
broken lines represent portions of the article which form no
part of the claimed design.

1 Claim, 14 Drawing Sheets
